ELECTRONIC COOKING RANGE

Yoshihumi Ura and Kouichi Sonoda, Osaka, Japan,
assignors to Sharp Kabushiki Kaisha

Filed Apr. 11, 1975, Ser. No. 567,414

Term of patent 14 years

Int. Cl. D7—02

U.S. Cl. D7—128

FIG.-1

FIG.-2

FIG.-3

FIG. 4

FIG. 5

FIG. 6

FIG. 7

FIG. 1 is a perspective view of an electronic cooking range showing our new design with the door partially open;

FIG. 2 is a front elevational view thereof, showing the door in a closed position and the electronic cooking range in an operating state with the interior illuminated;

FIG. 3 is a front elevational view of the electronic cooking range;

FIG. 4 is a plan view;

FIG. 5 is a bottom view;

FIG. 6 is a right side elevational view; and

FIG. 7 is a rear elevational view.

We claim:

The ornamental design for an electronic cooking range, as shown and described.
